UNITED STATES PATENT OFFICE.

DAVID B. BIRD, OF CHICAGO, ILLINOIS.

FULLER BALL.

1,399,459.

Specification of Letters Patent.

Patented Dec. 6, 1921.

Application filed September 10, 1920. Serial No. 409,312.

To all whom it may concern:

Be it known that I, DAVID B. BIRD, a citizen of the United States, residing at Chicago, in the county of Cook and State of Illinois, have invented certain new and useful Improvements in Fuller Balls, of which the following is a specification, reference being had to the accompanying drawings and to the reference characters marked thereon, which form a part of this specification.

This invention relates to new and useful improvements in Fuller balls for faucets and other devices where a removable, renewable valve closure may be used.

The principal object of my invention is to provide a Fuller ball for faucets, so constructed and arranged as to provide a proper closure for the valve; one which will have proper resiliency to compensate for ordinary wear and insure proper seating upon the valve surface, one which will be relatively cheap in construction and easily manipulated for the purpose of repairing or replacement by the non-skilled user; and also in the preferred form one which is provided with a reversible feature, thereby doubling its normal life and usefulness.

To this end, I provide a structure comprising a rod member adapted at one end to be connected with the crank or operating part of a faucet or other construction with which the Fuller ball may be used; a valve member proper consisting of an outer shell sufficiently strong for the purpose intended but yet of a somewhat resilient nature, and having a resilient interior or core such as rubber; and which shell, if intended to be reversible, may be made in two parts; a compression member adapted to contact with the interior core and to have longitudinal movement with respect to the shell portion, and screw threaded means engaging with the rod for effecting the longitudinal movement of the compression member.

The various advantages of my invention will be more manifest as I proceed with my specification.

In that form of the invention in which I have chosen to illustrate the same in the accompanying drawings:

Figure 1 depicts a conventional type of faucet in side view, with a portion broken

away in section to illustrate my improved Fuller ball in operative position.

Fig. 2 is a central vertical longitudinal view, enlarged, of the Fuller ball.

Figs. 3 and 4 are similar views, enlarged, showing modifications of the type shown in Figs. 1 and 2.

Referring now to said drawings, the letter A represents the faucet as a whole, having a handle B and an exteriorly screw threaded nipple C, by which the faucet A may be secured to the water supply pipe. The handle B may be connected by the screw D to a crank post E, which is provided at its lower end with an eccentrically mounted pin F.

The water inlet G of the faucet connects with the outlet chamber H, through the usual horizontal conduit or passageway I, on the inlet side of which conduit I is the usual annular valve seat J against which the Fuller ball represented as a whole by the letter K, will rest.

Referring now to Fig. 2, it will be seen that the Fuller ball K is composed of a rod 1, adapted at one end for engagement with the crank pin F, and provided at its opposite end with exterior screw threads 2. Intermediate its ends is an annular flanged shoulder 3. The Fuller ball has a hollow shell member 4 of the general shape and contour illustrated in Figs. 1 and 2, provided with a central recess or aperture through which the rod 1 will be passed so that the small tapered end of the shell 4 will rest against the annular flanged shoulder 3 on the rod. The shell 4, as shown, is filled with a resilient material, such as the rubber 5. An annular compression member 6 is adapted to fit within the open end of the shell 4 and have its interior face press against the rubber or other resilient material 5 therein. Means for compressing the member 6 against the core and also uniting it to the shell 4 is provided by the interiorly screw threaded recess 7 with which the screw threaded end 2 of the rod 1 is engaged. Thus the member 6 forms a closure for the open end of the shell 4.

In the modification shown in Fig. 4, the compression member 6 is somewhat larger in diameter than the one shown in Fig. 2. It is provided at its outer margin with an an-

nular interior recess or shouldered groove 8 adapted to receive the reduced portion or flange 9 of the end of the shell 4, the flange 9 engaging in the recess 8.

- 5 In the form shown in Fig. 2, where the compression member 6 is of a diameter to fit within the open end of the shell 4 and the two are held together solely by compression, and the engagement of the rod 1 with the 10 screw threaded recess 7, any tendency of the shell to expand may be avoided by the modification shown in Fig. 4.

In the two forms just described, it will be noted that the screw threaded recess 7 is 15 formed in the compression member 6, but this is not necessary, as the rod 1 may project through the compression member 6 and the screw threaded securing means associated with this member be in the form of a 20 nut adapted to engage the screw threaded end 2 of the rod and also bear upon the compression member 6. One form of this modification is illustrated in Fig. 3.

In said Fig. 3, the compression member 6 25 also serves as part of the shell. The rod 1 extends through said shell 6 and is engaged by a separate nut or screw threaded member 10. In this form the shell is made of two parts of the same exterior and interior con- 30 formation. Their open ends are provided with annular circumferential grooves, male and female, 11 and 12, and the shell 6 constitutes the compression member. When the nut 10 is screwed down upon the rod 1, it 35 will be manifest that the two halves of the shell, having telescopic engagement, are brought closer together, thus compressing the interior rubber core 5. In this modified form, the core will be made to conform to 40 the interior shape of the two half members 4 and 6 of the shell, instead of being of the conformation illustrated in Fig. 2, where a flat core surface is shown in contact with the flat face of the compression member 6. It 45 will also be manifest that in this form of arrangement, the outer surface of each shell member is equally adapted for engagement with or to seat upon the valve seat or sur- 50 face J. That shell member adjacent to the shouldered flange 3, will constitute the valve closure as it will rest or seat upon the valve seat J, and when this member becomes worn or damaged the nut 10 may be removed from the rod 1, the valve K reversed upon the rod, 55 and the parts brought together by replacing the nut 10, thus making the Fuller ball reversible, or doubling its life.

I prefer to make the shell 4 of a composition or mixture of hard Babbitt metal and 60 one rich in its tin content. A shell made of such an admixture produces a metal that will be sufficiently tough and rigid for ordinary uses and yet which will be somewhat resilient and nicely adapt itself to seat 65 against the valve seat J of the faucet. I

make no claim in this application to the composition of the metal from which the shell 4 is made, but reserve the right to make the same the subject of a separate application.

70

The many advantages of the construction shown and described will be manifest to those skilled in the art to which it appertains, without further elaboration.

75

I claim as my invention:

1. The Fuller ball comprising a crank rod, a thin metal shell member mounted thereon and adapted to coöperate with a valve seat, a resilient material within said shell member, a compression member bearing upon the resilient material, and the means associated with the crank rod and the compression member for securing said member and the shell member together.

80

2. In a Fuller ball construction, a crank rod, a resilient shell member mounted thereon and adapted for coöperation with a valve seat, a compression member mounted on said rod, a yielding filling material inclosed by the shell and compression members, and means coöperating with the crank rod for securing the compression member in operative position, said last mentioned member having relative movement with respect to the shell and being adapted to compress the filling material within the shell member.

85

3. In a Fuller ball construction, a crank rod adapted for operative connection with the crank pin of a faucet and provided intermediate its ends with an annular shoulder, a shell member of thin, somewhat resilient material mounted on the rod, a compression member also mounted on the rod, a resilient filling material completely inclosed by said members, and means for securing the compression member to the crank rod.

90

4. In a Fuller ball, the combination of a crank rod and a reversible valve member mounted thereon, said valve member comprising a two part shell provided interiorly with a resilient material, the parts of the valve member having telescopic engagement with each other, a nut member adapted to engage the rod member and one of the parts of the valve member.

95

5. In a Fuller ball construction, the combination with a crank rod and a hollow valve member of resilient material mounted thereon, of a compression member also mounted on said rod, and having telescopic engagement with the valve member, a filling of resilient material, and means associated with the compression member for actuating the said members to compress the filling material and securing the members together, said filling material being entirely inclosed by the two members.

100

6. A Fuller ball construction comprising a crank rod adapted at one end for operative connection with the crank pin of a faucet.

105

cet and at its other end provided with screw threads, an annular shoulder on said rod intermediate its ends, a shell member of thin metal having relative resiliency and adapted 5 for operative contact with a faucet valve seat, said shell member being supported on said rod and bearing against said annular shoulder, a rubber core filling said shell member, a compression member on said rod 10 to close the open end of the shell member and having contact with the rubber filling and a nut mounted upon the screw thread

end of the rod and adapted to secure the two members together, said rubber filling being completely incased by the shell and the compression members. 15

In testimony that I claim the foregoing as my invention I affix my signature, in the presence of two witnesses, this 7th day of September, 1920.

DAVID B. BIRD.
